UNITED STATES PATENT OFFICE.

ROY O. WILLIAMS, OF COLUMBUS, OHIO.

WELDER'S TOOL.

1,345,817.

Specification of Letters Patent.

Patented July 6, 1920.

Application filed August 4, 1919, Serial No. 315,058. Renewed May 15, 1920. Serial No. 381,745.

To all whom it may concern:

Be it known that I, Roy O. WILLIAMS, a citizen of the United States, residing at Columbus, in the county of Franklin and

5 State of Ohio, have invented certain new and useful Improvements in Welders' Tools, of which the following is a specification.

This invention relates to electric or arc welding, and has particular reference to an 10 improved tool for effecting the support and controlled manipulation of a welder's electrode, the object of the invention broadly being to provide a tool or holder for the purpose specified which is characterized by 15 lightness in weight and with corresponding freedom of movement and adjustment, and of such construction as to permit the same to be used for relatively extended periods without causing its operator undue fatigue 20 and to enable an operator to enlarge his working capacity.

Another object of the invention resides in a tool embodying the above mentioned characteristics and wherein is further 25 formed an improved clamping structure for grounding the feed wire of the tool upon the frame of the latter, and to render the clamp structure of a positive and reliable nature, so that when the tool is in use and 30 subject to jars and stresses, the wire retained by said clamp structure will be effectively prevented from becoming accidentally displaced and the operation of the tool impaired, said clamping structure consisting 35 essentially of a floating jaw having a fulcrum in the handle of the tool and having its opposite end adjustable with respect to the frame by means of a threaded element, whereby upon actuating said element the 40 free end of said jaw may be forced into engagement with a wire interposed between the jaw and the frame of the tool, so that the jaw may be caused to exercise friction upon the wire and effectively prevent the 45 latter from becoming displaced.

A further object of the invention resides in providing the metallic frame of the tool with an extended handle portion, which is of substantially spool shaped formation and 50 provides between its ends an annular cooling space, and said handle extremity being shaped to receive a fibrous handle tube which when placed around said handle extremity will inclose the heat circulating 55 chamber formed between the ends of said extremity, thus spacing the two from the

major portion of the metallic frame of the tool and rendering the latter convenient to operate by eliminating excessively heated portions, one end of said handle extremity 60 being formed with grooves, which serve to permit of the escape of heat from the heat circulating portion formed by said frame extremity.

A still further object of the invention 65 rests in a tool of the above nature and wherein is embodied a stationary and a movable jaw, said jaws having vertical openings formed therein which are capable of receiving the electrode wires, said openings being so positioned that when the movable jaw is spaced from the stationary jaw said openings will be substantially in registration and when said jaws are permitted to come together, said openings will be substantially staggered, so that the electrode wire passing therethrough will be caught by the offset walls of said openings and retained in fixed positions. 75

A further object of the invention resides 80 in a tool of the aforesaid character which constitutes an improvement upon the tool disclosed in my prior Patent No. 1,301,347, dated April 22, 1919.

With these and other objects in view, as 85 will appear as the description proceeds, the invention accordingly consists in the novel features of construction, combinations of elements and arrangement of parts, herein-after fully described and having the scope 90 thereof pointed out in the appended claims.

In the accompanying drawing, forming a part of this specification,

Figure 1 is a side elevation of the improved tool comprising the present invention. 95

Fig. 2 is a top plan view thereof,

Fig. 3 is a vertical sectional view taken through the rear or handle end of the tool, and

Fig. 4 is a detail perspective view of the wire clamping jaw.

Similar characters of reference denote like and corresponding parts throughout the several views of the drawing. 105

The tool A comprising the present invention is preferably used to support an electrode wire of the type employed for arc welding purposes, so that the electrode or wire may be brought to bear upon the work 110 at hand and to be capable of being manipulated with all requisite skill and conven-

ience. The tool is further designed to transmit current to the electrode and to successfully permit its operator to manipulate said electrode without being unnecessarily exposed to the heat of the latter. To this and other ends, the tool consists of a main frame 1, which is preferably formed from metal, and the forward end of said frame is formed to constitute a stationary jaw 2 and a plurality of upstanding and spaced ears 3. The jaw 2 terminates rearwardly in an extended and longitudinally disposed shank portion 4 which terminates in a substantially spool shaped manipulating extremity 5, and between the ears 3 and the extremities 5 there is provided an integral upstanding frame 6. Pivoted between the ears 3 is a movable jaw 7, which is designed to be moved relatively with respect to the stationary jaw 2 and to be of such construction as to permit of the clamping of an electrode between said jaws. To release or clamp an electrode with respect to the jaws, said movable jaw is formed with an actuating extremity 8 which is extended so as to operate within the superposed frame 6. The extremity 8 is suitably bifurcated as at 9, and receives a thumb piece 10, the latter being of a substantially different material than the extremity 8 and is of such material as to offer resistance to the transmission of heat from the extremity 8. In this manner the temperature of the thumb piece 10 is maintained below that of the movable jaw 7 under actual working conditions, so that the jaw 7 may be operated at any time without causing discomfort or physical injury to the operator. This principle of cooling the manipulating end of the movable jaw handle has been clearly set forth, however, in my aforesaid patent. A coil spring 11 is interposed between the bifurcated end 9 of the handle extremity 8 and the shank portion 4 of the frame 1, and the normal tendency of said spring is to maintain a movable jaw in closed relation with respect to the stationary jaw, so that an electrode positioned between said jaws will be securely gripped without involving the agency of manual pressure. The meeting faces of said jaws may be suitably secured as at 12 so as to increase the gripping effectiveness of the jaws.

The jaws 2 and 7, in the present form of the invention, are capable of clamping an electrode in both horizontal and vertical positions. Obviously, when an electrode passes between the flat meeting faces of said jaws the same will be maintained in a horizontal position, but under conditions where an electrode is drawn from a spool it is desirable that the electrode pass vertically through the jaws. To secure an electrode in this position, said jaws are provided with one or more sets of registering openings 13, each

set being of a substantially different diameter in order to accommodate wires or electrodes of varying diameters or gage. The openings 13 are so located that when the jaws are in separated relation, said openings will be in alinement or in vertical registration. This permits an electrode to be passed through the jaws in a convenient manner. However, to grip the electrode, the movable jaw 7 is released so that the same will return to its adjacent relation with respect to the stationary jaw by the action of the spring 11. The movement of the movable jaw results in bringing the openings 13 of said jaws out of registration with one another, so that the walls of said openings will impinge against the electrodes to effectively clamp the latter to the tool. Thus, when an electrode has been substantially used up, the same may be replaced by merely depressing the thumb piece 10, which results in alining the openings 13. The tool is then bodily moved in an upward direction upon the electrode until a suitable length of the latter has been afforded. Then by releasing the thumb piece, said movable jaw will return to its normally closed position and the electrode contained within the openings 13 will be gripped by virtue of the offset relation of the walls of said openings. This construction has the advantage of enabling an operator to secure an electrode of any desired length without in any way fingering the electrode or subjecting himself to physical danger. It will thus be apparent that one of the objects of the invention, that is, the provision of a tool which will be safe and convenient to operate, is carried out by the provision of the openings 13 which facilitate the handling of an electrode.

The rear manipulating extremity 5 of the main frame 1 is substantially of smooth shaped formation and is formed to provide a longitudinally extending port 14 therein, through which the conductor wire 15 of the tool extends. To enable the tool to be grasped, the extremity 5 is provided with a tubular handle 16, which is preferably formed from a fibrous insulating material. This tube is adapted to be slipped over the manipulating extremity 5 and when thus positioned, said handle will be substantially spaced from the major portion of the extremity 5 by virtue of the spool shaped formation of the latter, thus a heat circulating or cooling space 17 is defined between the enlarged ends of the extremity 5. It will be observed that the latter are grooved so that air may circulate into and around the space 17, thus maintaining the latter cool under working conditions and preventing its heat from spreading to any appreciable extent to the handle 16. The handle is retained in position upon the extremity 5 by providing the latter with an adjustable head

- screw 18 and by providing an opening 19 in the handle. Obviously, by inserting the tool through the opening 19, said screw may be so adjusted as to enable its head to frictionally press upon the inner wall of the handle, and sufficient pressure may be thus exercised to prevent accidental removal of said handle. Thus it will be manifest that this manner of securing the handle 16 with the frame 1 will serve to maintain said handle in a relatively cool condition when the same is actively employed and that in combination with the thumb piece 10 the liability of injury to the operator, by reason of heated portions in the tool, will be reduced to a minimum.
- In order to firmly secure the lead wire 15 in a grounded position upon the frame 1, use is made of a clamping bar 20. The latter has its rear end loosely mounted upon shoulders 21 formed at the forward end of the bore 14, and the forward end of said bar is provided with a threaded opening 22 which is adapted to register with a plain opening 23 formed in the underside of the shank 4. It will be noted that the forward end of said bar projects inside of the superposed frame 6 and is guided for oscillatory movement by this frame. A screw 24 projects through the openings 23 and is adapted to be threaded into the opening 22, whereby upon the tightening of said screw said bar will have its forward but free end drawn toward the bottom of the shank portion 4.
- The underside of the bar 20 is provided with a knife edge 25 which is adapted to coöperate with a similar edge 26 formed on the shank portion 4. The bared portion of the wire 15 is passed between the edges 25 and 26, and obviously, by tightening the screw 18, said edges may be drawn together in a manner calculated to effectively grip said wire so that the same will be securely held in connection with the tool and capable of withstanding and maintaining the connection under the stresses and pulls of working conditions. If desired, a shield 27 may be placed upon the handle 16 so as to further protect the hand of the operator from the heat emitted by the electrode.
- From the foregoing description taken in connection with the accompanying drawing, it will be apparent that there is provided a tool of considerable utility in its own field. By virtue of the construction described improved means have been provided for clamping the wire in connection with the tool, and for preventing said wire from becoming accidentally disconnected with respect to its grounded position upon the tool. Also, mechanism has been provided for retaining the main handle at a low temperature under working conditions, and through the provision of the openings in the jaws 2 and 7, means have been provided for effectively clamping the vertically extending electrode in connection with the tool. In view of the foregoing description it is believed that the many advantages of the tool, as well as its operation, will be clearly understood by those versed in the art, and therefore a more extended explanation has been accordingly omitted.
- What I claim is:
1. In an electrode holder, a main structure, 75 a stationary jaw member forming a part of said structure, a movable jaw member pivotally carried by said structure, and said jaw members being provided with coöperative openings extending perpendicularly therethrough, said openings being arranged substantially in registration when said jaw members are separated and out of registration when said members are in closed relation.
  2. In an electrode holder, a main structure, 80 a stationary jaw member forming a part of said main structure, a movable jaw member pivotally carried by said structure, an actuating handle for said member, a spring arranged between said handle and said structure and tending to maintain said movable jaw in closed relation with said stationary jaw, and said jaws being provided with openings arranged perpendicularly therein 85 and said openings being so disposed as to assume staggered positions when said jaw members are in closed relation.
  3. In an electrode holder, a main frame, 90 jaws carried by said frame and arranged to receive an electrode, a spool shaped projection formed upon the rear end of said frame, a tubular handle fitted around said projection, said handle serving to define in conjunction with said projection an air circulating space, and the ends of said projection being grooved to permit of the continuous circulation of air through said space from exterior sources.
  4. In an electrode holder, a main frame, 100 jaws carried by said frame and arranged to receive an electrode, an extension formed upon the rear end of said frame, a screw threadedly carried by said extension, a tubular sleeve formed to be fitted over said extension, and said sleeve having an opening formed therein designed for registration with said screw, whereby said screw may be exteriorly actuated to be brought into retaining relation with said handle.
  5. A tool of the character described, a main frame, means carried by the forward end of said frame for retaining an electrode in secured relation therewith, an extension 110 formed upon the rear end of said frame and having a longitudinal bore formed therein, a clamping bar pivotally seated in the forward end of said port, and means for binding said bar in clamping relation with a conductor passing through said port.

6. In a tool of the character described, a main frame, means carried by the forward end of said frame for securing an electrode thereto, an extension formed upon the rear end of said frame, said extension having a longitudinally extending port formed therein, a clamping element, knife edges formed upon said frame and element, and means for drawing said clamping element so that a wire passing through said port will be clamped between the edge thereof and the edge of said frame.
- 5 7. In an electrode holder, a main frame, 10
- jaw means disposed at the forward end of said frame, an extension formed upon the rear end of said frame, said extension having a longitudinally extending opening formed therein, a clamping bar having its rear end pivotally seated within the forward end of said opening and means for drawing said bar toward said frame and to confine a conductor passing through said port between said bar and said frame. 15 20

In testimony whereof I affix my signature.

ROY O. WILLIAMS.
